UNITED STATES PATENT OFFICE.

FRANK G. McPHERSON AND THOMAS C. McPHERSON, OF BEAVER FALLS, PENNSYLVANIA, ASSIGNORS TO KEYSTONE WIRE MATTING CO., OF BEAVER FALLS, PENNSYLVANIA.

MAT.

1,090,161.

Specification of Letters Patent. Patented Mar. 17, 1914.

Application filed January 27, 1913. Serial No. 744,494.

To all whom it may concern:

Be it known that we, FRANK G. McPHERSON and THOMAS C. McPHERSON, citizens of the United States, residing at 5 Beaver Falls, in the county of Beaver and State of Pennsylvania, have invented a new and useful Mat, of which the following is a specification.

The invention relates to improvements in 10 mats.

The object of the present invention is to improve the construction of that type of mat, illustrated and described in a patent granted to Thomas C. McPherson, Mar. 7, 15 1905, No. 784,222, and to provide a flexible mat composed of hingedly connected sections equipped with spaced pad or mat blocks and provided with simple and inexpensive means for completely binding the 20 blocks, whereby a mat of great strength and durability is produced.

With these and other objects in view, the invention consists in the construction and novel combination of parts hereinafter fully 25 described, illustrated in the accompanying drawings, and pointed out in the claims hereto appended; it being understood that various changes in the form, proportion, size and minor details of construction, with- 30 in the scope of the claims, may be resorted to without departing from the spirit or sacrificing any of the advantages of the invention.

In the drawings:—Figure 1 is a plan 35 view of a portion of a mat, constructed in accordance with this invention. Fig. 2 is an enlarged horizontal sectional view of a portion of the mat. Fig. 3 is a plan view of the mat, illustrating another form of the 40 blocks. Fig. 4 is a detail sectional view on the line 4—4 of Fig. 1. Fig. 5 is a similar view on the line 5—5 of Fig. 1. Fig. 6 is a detail perspective view, illustrating the arrangement of the terminal portions of the 45 binding strips of one of the sections.

Like numerals of reference designate corresponding parts in all the figures of the drawings.

In the accompanying drawings in which 50 is illustrated the preferred embodiment of

the invention, the mat comprises in its construction a plurality of sections hinged together, the sections being preferably disposed transversely of a mat when the same is of oblong form, and the mats may be of 55 any size and the sections may extend in either direction as will be readily understood. The sections of the mat shown in Figs. 1 and 2 are equipped with oblong blocks 1, designed to be constructed of cork 60 or other suitable material and arranged in spaced relation, the blocks of the adjacent rows being alternately arranged, so that the ends of the blocks of each row are located opposite or in alignment with the intervals 65 or spaces between the blocks of the adjacent rows. Each end row of a mat has its blocks preferably arranged so that its terminal blocks will occur at the corners of the mat, one end portion of the mat being illustrated 70 in Fig. 1 and the blocks of the marginal end row thereof being arranged in this manner. This arrangement provides a strong corner construction, but a mat may be made up of any desired number of rows, and the 75 terminal blocks of the marginal row may occur in the corners of the mat or otherwise.

The blocks 1 of the marginal row or section and each alternate row are bound by strips 2, arranged in pairs and constructed 80 of metal of a width slightly less than the thickness of the blocks and oppositely bent at intervals to form similar approximately U-shaped bends or loops 3, which open toward each other and embrace the blocks and 85 form complete metallic bindings for the same. The upper and lower edges of the metallic binding strips terminate short of the upper and lower faces of the blocks, which project slightly beyond the metallic 90 binding so as to present yielding surfaces to the supporting surface on which the mat is placed and also to the feet. Each of the loops or bends of the strips 2 preferably extends around one half of a block, and while 95 each of the strips 2 is preferably constructed of a single piece of metal of sufficient length to extend entirely across the mat, this, of course, is not essential and one or more pieces may be employed in the construction 100

of a binding strip. The binding strips are bent at the corners of the blocks and also at points intermediate of the ends thereof to form straight intervening connecting portions 4, which abut against each other. The straight intervening connection portions, which are located between the spaced blocks, may be secured together by rivets 5, or any other suitable fastening means. By this construction, the fastening means are located beyond the blocks in the spaces between the same.

The terminal portions 6 of the binding strips 2 are located at the outer side edges of the end blocks of the sections, and are overlapped and secured together by a rivet 7, or other suitable fastening device, and they are preferably reduced at the side edges to form recesses 8 for the reception of cap plates 9. The cap plates 9, which are approximately U-shaped in cross section, have their side portions fitted against the upper and lower edges of the recessed terminal portions 6 of the strips 2, and they are provided with inturned longitudinal edges, which form flanges 10 for engaging the back of the overlapped terminal portions 6 of the said binding strips. The cap plates are preferably constructed of pliable metal and before being applied to the mat are open a sufficient distance to permit them to be placed in position, after which they are compressed into engagement with the end portions of the binding strips 2. The recessing of the terminal portions 6 of the binding strips 2 arranges the upper and lower side portions of the cap plates in flush relation with the upper and lower faces of the mat.

The blocks of the rows between those having the binding strips 2 are bound by metallic strips 11, constructed and arranged similar to the metallic strips 2 with the exception of their terminal portions 12, which are bent outwardly from the adjacent straight abutting portions and overlap slightly the terminal loops or bends of the strips 2. The terminal portions 12 are provided at their ends with perforations for the reception of pintle rods 13 of wire, or other suitable material, piercing the end portions of the blocks and the metallic binding loops thereof and having their terminals 14 arranged exteriorly of the terminals 6 of the binding strips 2 and bent inwardly toward each other and arranged beneath the cap plates 9, as clearly illustrated in Fig. 2 of the drawings. The blocks of rows of a mat are arranged in overlapping relation, and the pintle rods hinge the sections of the mat together and form a flexible mat and enable the same to be readily folded over for sweeping beneath the same, or for any other purpose. The pintle rods piercing the ends of

the blocks assist in retaining the same in 65 the metallic bindings, and the blocks are also pierced by bracing and retaining rods 15 and 16, constructed of wire or other suitable material and extending through the blocks adjacent to the centers thereof. The combined bracing and retaining rods 15 extend to the sides of the mat and pierce the adjacent terminals 6 of the strips 2 and have their ends concealed by and arranged beneath the cap plates. The rods 16, which occur at the 75 intervening sections having the metallic binding strips 11, preferably terminate at the outer sides of the end blocks of such sections and have angularly bent terminal portions 17, which are bent against the adjacent binding strips, whereby the rods 16 are securely retained in place.

The blocks 1 shown in Figs. 1 and 2 of the drawings are of uniform size and shape, but the mat may be equipped with blocks of 85 different sizes and shapes, and in Fig. 3 of the drawings is illustrated a mat equipped with approximately triangular blocks 18 and oblong blocks 19. Blocks, however, of any other desired form may, of course, be 90 employed, and metallic binding strips 20 and 21 of the mat shown in Fig. 3 are constructed and arranged substantially the same as the binding strips illustrated in Figs. 1 and 2, the only difference residing in the shape 95 of the binding portions or loops, which are bent to conform to the configuration of the blocks 18 and 19.

The ends of the mat are preferably bound by a rod of wire or other suitable material 100 22, bent in the form of a link with the terminals arranged at the inner side thereof. The inner side of the link pierces the outer ends of the blocks and the binding loops of the end row or section. The binding rod 105 supports coiled springs 23, arranged at intervals and located at the spaces between the outer ends of the blocks through which the binding rod passes.

What is claimed is:—

1. A mat of the class described including a plurality of spaced blocks arranged in rows, the blocks of each row being located at the terminals or spaces between the blocks of the adjacent rows, and binding 115 strips for each row bent at intervals to form opposite bends or loops, which embrace and extend entirely around the edges of the blocks to form a complete binding therefor, said strips having intervening connecting 120 portions secured together at the spaces between the blocks.

2. A mat of the class described including a plurality of rows of spaced blocks, the blocks of each row being located at the intervals or spaces between the blocks of the adjacent rows, and binding strips for each row bent at intervals to form opposite bends

or loops, which embrace and extend entirely around the edges of the blocks to form a complete binding therefor, said strips having intervening connecting portions abutting at the spaces between the blocks, the connecting abutting portions of the adjacent rows being staggered, and fastening means located at the spaces between the blocks for securing the abutting portions of the binding strips together.

3. A mat of the class described including a plurality of spaced blocks arranged in rows, the blocks of each row being located at the intervals between the blocks of the adjacent rows, a binding strip for each row bent at intervals to partially embrace the blocks, a co-acting binding strip also bent at intervals to partially embrace the blocks, said binding strips operating to form a complete binding which extends entirely around the edges of the blocks, said strips being brought together in abutting relation between each block, and fastening means for securing the strips together at the places where they abut.

4. A mat of the class described including a plurality of spaced blocks arranged in rows, the blocks of each row being located at the intervals or spaces between the blocks of the adjacent rows, and binding strips for each row bent at intervals to form corresponding loops or bends and straight intervening connecting portions, said loops or bends opening toward each other and fitted against the edges of the blocks and forming a complete binding around the same, and fastening means for securing the straight connecting portions of the binding strips together in abutting relation.

40 5. A mat of the class described including a plurality of rows of spaced blocks, the blocks of each row being arranged opposite the intervals between the blocks of the adjacent rows, binding strips arranged in pairs and extending along the rows and bowed at intervals and embracing the side edges of the blocks and extending completely around the same to form bindings therefor and secured together between the blocks, and rods piercing the blocks and the strips of the adjacent rows and retaining the former in the said bindings.

6. A mat of the class described including a plurality of rows of spaced blocks, the blocks of each row being arranged opposite the intervals between the blocks of the adjacent rows, binding strips arranged in pairs and extending along the rows and bowed at intervals and embracing the side edges of the blocks and extending completely around the same to form bindings therefor and secured together between the blocks, and rods extending longitudinally of the rows and piercing the blocks and the

bindings and hinging the rows of blocks to one another to form a flexible mat.

7. A mat of the class described including a plurality of rows of spaced blocks, the blocks of each row being arranged opposite the intervals between the blocks of the adjacent rows, binding strips arranged in pairs and bowed at intervals and embracing the side edges of the blocks and extending completely around the same to form bindings therefor, pintle rods piercing the end portions of the blocks and the strips and hinging the rows of blocks to one another, and combined bracing and retaining rods extending longitudinally of the rows and piercing the blocks and the strips at points intermediate of the ends of the said blocks to retain the latter in the said bindings.

8. A mat of the class described including a plurality of rows of spaced blocks, and binding strips arranged in pairs and oppositely bowed at intervals to fit around and form complete bindings for the said blocks, the terminals of the strips of the alternate rows being bent inwardly toward each other and terminating at the ends of the rows of the blocks and the terminals of the strips of the other rows being bent in opposite directions and overlapping the said inwardly bent terminals, and means for connecting the terminals of the strips of the several rows.

9. A mat of the class described including a plurality of rows of spaced blocks, and binding strips arranged in pairs and oppositely bowed at intervals to fit around and form complete bindings for the said blocks and terminating at the ends of the said rows, the terminals of the strips of the alternate rows being bent inwardly toward each other and the terminals of the strips of the other rows being bent in opposite directions and overlapping the said inwardly bent terminals, pintle rods piercing the blocks and the terminal portions of the said strips and having their ends bent against the inwardly extending terminals of the said strips, and cap plates mounted on the said inwardly bent terminals and concealing the ends of the pintle rods.

10. A mat of the class described including a plurality of rows of blocks arranged at intervals, binding strips arranged in pairs and oppositely bowed or bent at intervals to embrace and bind completely the edges of the blocks and terminating at the ends of the said rows, the terminals of the strips of the alternate rows being bent inwardly toward each other and recessed at the upper and lower edges, and the terminals of the strips of the other rows being extended in the opposite direction and overlapping the said inwardly bent terminals, pintle rods piercing the overlapped end portions of the

blocks and having their ends bent against the said inwardly extending terminals of the said strips, and approximately U-shaped cap plates arranged on the recessed terminals of the said strips and having flanges engaging back of the same and covering the terminals of the said pintle rods.

In testimony, that we claim the foregoing

as our own, we have hereto affixed our signatures in the presence of two witnesses.
